UNITED STATES PATENT OFFICE.

ARTHUR F. RAYMOND, ALPHONSE MATHIEU, AND CYRIL LAVALLE, OF WEBSTER,
MASSACHUSETTS.

LOOM.

1,296,697.

Specification of Letters Patent. Patented Mar. 11, 1919.

Application filed March 19, 1917. Serial No. 155,915.

To all whom it may concern:

Be it known that we, ARTHUR F. RAYMOND, ALPHONSE MATHIEU, and CYRIL LAVALLE, all citizens of the United States, residing at Webster, in the county of Worcester and Commonwealth of Massachusetts, have invented a new and useful Improvement in Looms, of which the following, together with the accompanying drawing, is

10 a specification.

The present invention relates to looms, and more particularly to improvements associated with the picking mechanism of a loom and designed to safeguard the operation of 15 the same by preventing the sagging and entanglement of the weft or shuttle thread, especially when two or more shuttles are employed.

The invention resides in the application 20 to a shuttle box of means for firmly retaining and gripping the shuttle thread each time the shuttle is sent fully "home" in said box, so that the projecting portion of the thread, beyond the shuttle box, is held taut, 25 and is prevented from sagging and thus becoming entangled with any of the other shuttle threads of the loom. We have shown our invention embodied in convenient form as an attachment to existing shuttle boxes of 30 well known construction, the same being applicable to such shuttle boxes without necessitating any changes in the latter; however, it is to be understood that our invention is in no sense limited to the construction herein 35 shown and described, but that its essential features are applicable to any and all types of picking mechanism in which it is found desirable to prevent the sagging and entanglement of the shuttle thread, regardless 40 of the manner in which it is applied thereto.

Our invention is fully set forth in the following description and illustrated in the accompanying drawings, in which—

Figure 1 is a front view of a well known 45 form of shuttle box having our invention applied thereto.

Fig. 2 is a section on line 2—2, Fig. 1, showing the parts in the positions which

they assume when the shuttle is driven "home" in the box. 50

Fig. 3 is a view similar to Fig. 2, but showing the parts in the positions assumed in the absence of a shuttle.

Fig. 4 is a sectional view on line 4—4, 55 Fig. 1.

Like reference characters refer to like parts in the different figures.

We have illustrated our invention in connection with a shuttle box of well known construction, here shown as of the multiple 60 type embodying superposed raceways 1 and 2 for the traverse of a pair of shuttles, but obviously the number of such raceways and shuttles may be increased indefinitely. The raceway for each shuttle is constituted by the 65 back wall 3 of the box, and the horizontal partition 4 or 4', as the case may be, on which the shuttle slides, there being the usual clearance between said shuttle and the front wall 5 of the box. In the manner common to devices of this class, the front of the box, at the end remote from the wall 5 provides bearing lugs 6, 6, for a shaft 7, on which are journaled the usual swells or shuttle binders 8, 8. The latter are urged inwardly 70 by the springs 9, so that as the shuttles move to the right, Fig. 1, in their raceways, the central portions of the swells 8 are pressed yieldingly against the shuttles to arrest their 75 movement and to prevent rebound, in the usual manner. The free ends of the swells 8 are limited in their outward movement by a rod 10 which is carried by lugs 11 on the front wall 5 of the box. 80

It will be understood that when a shuttle is driven "home" in the box, by reaching the end of its movement to the right, Fig. 1, the weft thread carried thereby, as shown at 12, Figs. 1 and 4, is ordinarily liable to sag downwardly or to be pulled out of place by 85 the beating action on the fabric, and our invention aims to provide a gripping mechanism for said thread, to hold the latter taut when its shuttle is at rest within the box and to release said thread just as soon as said 90 shuttle begins its next succeeding pick. To 95

this end, it is proposed to clamp the thread 12 against the rear face of front wall 5, within the raceway in which the corresponding shuttle travels, the clamping mechanism being rendered operative by the arrival of the shuttle at the end of its movement in said raceway. In order to adapt this clamping mechanism to the shuttle boxes now in ordinary use, the operating mechanism therefor may conveniently be mounted on a pair of brackets 13 and 14, which are carried on the shaft 7 between the bearing lugs 6 thereof and the interposed pivoted swell or shuttle binder 8. The upper bracket 13 of each 10 bar has pivoted thereto at 15 a depending arm 16, which has a projection 17 adapted to be struck by the shuttle 18, Fig. 2. In the absence of a shuttle within the raceway, the depending arm 16 is held yieldingly by a spring 19 in the position shown in Fig. 3, with the projection 17 in the path of the front side of a shuttle. The lower end of the arm 16 is formed with a segmental rack 20, which is in mesh with a pinion 21 on a rod 22, the latter being journaled, adjacent said pinion, in a bearing provided by the lower bracket 14 of the pair of brackets hereinbefore referred to. The rod 22 is extended to the other end of the shuttle box, where it 20 may be supported in a journal 23 attached to the under side of the corresponding horizontal partition 4 or 4', on which the shuttle 18 travels.

The rod 22 has secured to its end a clamping member 24, which normally lies in the 30 position shown in Fig. 3 below the partition 4 on which the shuttle 18 travels, the spring 19 acting on the arm 16 to rotate the rod 22 in a counterclockwise direction. When 40 the shuttle is driven "home" in the box the front face thereof at its advanced end becomes gradually more and more effective against projection 17, owing to the taper of the shuttle, to rock the arm 16 from the position shown in Fig. 3 into the position shown in Fig. 2. The movement of arm 16 is transmitted through rack 20 and pinion 21 to rotate rod 22, thereby moving the clamping member 24 into the position shown 45 in Figs. 2 and 4, where it grips the thread 12 against the rear face of the front wall 5 within the raceway. As soon as the next pick of the shuttle begins, the spring 19 becomes effective to return the arm 16 to the 50 position shown in Fig. 3, thus releasing the thread from the clamping member 24 and causing said member to move downwardly, out of the path of the shuttle and the thread 12 carried thereby.

60 We claim,

1. In a loom, means for clamping the weft thread at the open end of the shuttle box, and means, located at the closed end of the shuttle box and actuated by the shuttle, for

operating said clamping means, said operating means extending into the path of the shuttle. 65

2. In a loom, means for clamping the weft thread located at the open end of the shuttle box, and means actuated by the shuttle 70 after it has entered the shuttle box for bringing said clamping means into action.

3. In a loom, the combination with a shuttle box and a shuttle having a tapered end, of means for clamping the weft thread 75 at the open end of the shuttle box, and means located within the shuttle box and actuated by the tapered end of the shuttle for operating said clamping means.

4. In a loom, the combination with a shuttle box and a shuttle, of means for clamping the weft thread against the vertical wall of the shuttle box at the open end of the shuttle box, and means located in the shuttle box and actuated by the shuttle for operating 85 said clamping means.

5. In a loom, the combination with a shuttle box and traveling shuttle, of means for clamping the shuttle thread at one end of said box, and actuated by the shuttle upon 90 its arrival at the other end of said box.

6. In a loom, the combination with a shuttle box and a traveling shuttle, of means for clamping the weft thread at the open end of the shuttle box, means located in the shuttle 95 box and actuated by the shuttle for bringing said clamping means into action, and means operative upon the movement of the shuttle out of the shuttle box for releasing said clamping means. 100

7. In a loom, the combination with the shuttle box, of means for clamping the weft thread at the open end of the box, means at the opposite or closed end of the shuttle box for actuating said clamping means, comprising a swinging lever in the path of the shuttle and a spring for reversing said lever and the clamping means as the shuttle begins its return movement. 105

8. In a loom, means for clamping the weft thread at the open end of the shuttle box, means for actuating the clamping means located at the opposite end of the shuttle box and in the path of the shuttle, a rocking shaft connecting said clamping means and 115 said actuating means, and means for reversing the clamping means as the shuttle begins its return movement.

9. In a loom, means for clamping the weft thread at the open end of the shuttle box, 120 means located at the opposite or closed end of the shuttle box and in the path of the shuttle for actuating said clamping means, said actuating means comprising a pivoted swinging lever, a rack carried by said lever 125 and curved concentrically with the pivot of the lever, a rocking shaft operatively connected with the clamping means, a pinion

carried by said rocking shaft in engagement with said curved rack, and a spring for reversing said swinging lever as the shuttle leaves the shuttle box.

5 10. In a loom, means for clamping the weft thread at the open end of the shuttle box, means actuated by the advancing end of the shuttle for operating the clamping means, and means for releasing the weft

thread upon the reverse movement of the 10 shuttle.
